CLOSURE FOR CONTAINER COVERS

George Lambert, New York, N. Y.

Substituted for abandoned application Serial No. 508,475, November 1, 1943. This application July 24, 1945, Serial No. 606,837

3 Claims. (Cl. 222—559)

1

This invention relates to new and useful improvements in a closure for a container cover.

This is a substitute for my original application filed November 1, 1943, Serial Number 508,475.

More specifically, the invention contemplates the construction of a closure for a container cover, which is characterized by an annular skirt wall for engagement on said container, and a transverse wall mounted across said skirt wall and positioned slightly downwards from the top edge of said skirt wall and being formed with an opening closable with an improved closure member.

It is proposed that the improved closure member be rested upon the top face of said transverse wall and be adapted to move from a position over said opening to a position to one side of the opening.

It is proposed that said skirt wall be provided with bayonet slots or openings formed on the opposite sides of said cover and above said transverse wall. It is proposed that a string or strings extend from the opposite sides of said closure member and through said bayonet slots whereby said strings may be manipulated to move said closure member partly or fully off or on said opening. It is further proposed to manipulate said strings in said bayonet slots or openings for frictionally holding said closure member in a stationary selected position.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a perspective view of a container with a cover having a closure constructed in accordance with this invention.

Fig. 2 is a plan view of Fig. 1 but illustrated with the closure member in an open position.

Fig. 3 is a fragmentary vertical sectional view taken on the line 3—3 of Fig. 1.

Fig. 4 is a fragmentary enlarged sectional view taken on the line 4—4 of Fig. 1.

Fig. 5 is a side elevational view of a container of a modified form provided with a cover constructed in accordance with this invention.

The cover for a container 10, in accordance with this invention, includes a skirt wall 11 for engagement upon the top of said container 10. The skirt wall 11 has a beaded upper edge 11a

provided with a groove 11b disposed around its inner periphery, and a transverse wall 12 is mounted across said skirt wall and positioned slightly downward from the top edge of the skirt wall 11 with its peripheral edges engaging the groove 11b, and formed with an opening 13. A closure member 14 rests on the top face of the transverse wall 12 and is adapted to close said opening 13. The skirt wall is formed of spaced wall portions forming a channel into which the top edge portion of the container 10 extends, see Fig. 3.

The skirt wall 11 is formed with bayonet slots 15 having large ends 16, and small ends 17 directed outwards. These bayonet slots 15 are formed in opposite sides of the top portion of the skirt wall 11 and on a level with the top of the transverse wall 12. A string 18 has loop portions extending from opposite sides of said closure member 14 and through the large ends 16 of said bayonet slots 15. As illustrated, the string 18 is formed from a length of string having its ends tied together into a knot 19. Intermediate portions of the continuous length of string are engaged through holes 20 formed in the closure member 14 by which the closure member 14 is rigidly attached on portions of said string.

The string 18 has a loop portion extended forward and a loop portion extended rearwards. The forwardly extending loop portion is engaged through a spaced pair of said bayonet slots 15 on the front side of the skirt wall 11 and the back loop is engaged through spaced bayonet slots 15 at the back side of the skirt wall 11. Each bayonet slot 15 has a slot 21 extended inwards from the top edge of the skirt wall 11 of the cover through which the string 18 may be slipped into and removed from the bayonet slots, as desired.

In Fig. 1 the string 18 is shown passing through the large ends 16 of the bayonet slots 15. The closure member 14 is shown engaged over and closing the opening 13. In this condition the back loop of the string 18 may be pulled for moving the closure member 14 into an open position, as illustrated in Fig. 2. When it is desired to close the opening 13 it is merely necessary to pull the front loop of the string 18 to a position as illustrated in Fig. 1. The knot 19 facilitates gripping the back loop of the string 18 by which it may be easily pulled. A button or knot 22 is formed centrally on the front loop by which the front loop of said string or strips 18 may be easily gripped and pulled.

The closure member 14 may be releasably held in a stationary position closing the opening 13 or partially closing said opening, or in an open position, merely by forcing the side portions of the loops of string 18 into the small ends 17 of the bayonet slots. The dot and dash lines 18' in Fig. 4 illustrate the new position of the string 18. In the new positions the top and bottom edges of the small ends of the bayonet slots 15 grip and hold the string 18 and so indirectly hold the closure 14 as selected.

In Fig. 5 another embodiment of the invention is shown in which the new cover is applied to a container 10' having a side handle 24. This container 10' is provided with a cover constructed identically as disclosed in Figs. 1 to 4. In other respects this form of the invention is identical to the previous form and like parts are indicated by like reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In combination with a cover for a container having a transverse wall surrounded by a skirt wall having a portion projected above the top face of the transverse wall and formed with an opening in one side thereof adjacent the skirt wall, means for closing the opening in the transverse wall, comprising a closure member rested on the top face of the transverse wall and of a size greater than the opening, the portion of the skirt wall projected above the transverse wall being formed on opposite sides of the opening with opposed pairs of slots on a level with the top face of said closure member, and a continuous string having loop portions extending from the top face of said closure member on opposite sides thereof, said loop portions being slidably extended through said opposed pairs of slots to be pulled in one direction to position said closure member over the opening or in the opposite direction to position said closure member on the top face of the transverse wall to one side of the opening.

2. In combination with a cover for a container having a transverse wall surrounded by a skirt wall having a portion projected above the top face of the transverse wall and formed with an opening in one side thereof adjacent the skirt wall, means for closing the opening in the transverse wall, comprising a closure member rested on the top face of the transverse wall and of a size greater than the opening, the portion of the skirt wall projected above the transverse wall being formed on opposite sides of the opening with opposed pairs of slots on a level with the

top face of said closure member, and a continuous string having loop portions extending from the top face of said closure member on opposite sides thereof, said loop portions being slidably extended through said opposed pairs of slots to be pulled in one direction to position said closure member over the opening or in the opposite direction to position said closure member on the top face of the transverse wall to one side of the opening, said slots having large ends through which said loop portions freely slide and small ends into which said loop portions may be forced to frictionally hold the string with said closure member in either of its two positions.

3. In combination with a cover for a container having a transverse wall surrounded by a skirt wall having a portion projected above the top face of the transverse wall and formed with an opening in one side thereof adjacent the skirt wall, means for closing the opening in the transverse wall, comprising a closure member rested on the top face of the transverse wall and of a size greater than the opening, the portion of the skirt wall projected above the transverse wall being formed on opposite sides of the opening with opposed pairs of slots on a level with the top face of said closure member, and a continuous string having loop portions extending from the top face of said closure member on opposite sides thereof, said loop portions being slidably extended through said opposed pairs of slots to be pulled in one direction to position said closure member over the opening or in the opposite direction to position said closure member on the top face of the transverse wall to one side of the opening, said slots having large ends through which said loop portions freely slide and small ends into which said loop portions may be forced to frictionally hold the string with said closure member in either of its two positions, said skirt wall being formed with narrow slots leading from the top edge of the skirt wall to said pairs of slots through which the loop portions of said string may be passed to be engaged with and disengaged from said pairs of slots.

GEORGE LAMBERT.
